(57) CLAIM

The ornamental design for a communication device cradle, as shown and described.

DESCRIPTION

FIG. 1 is a back view of a communication device cradle showing my design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 shows a back perspective view of the communication device cradle of my design;

FIG. 8 shows a front perspective view of the communication device cradle of my design; and,

FIG. 9 shows an opposite front perspective view of the communication device cradle of my design.
